UNITED STATES PATENT OFFICE.

CHARLES D. CHASE, OF ST. LOUIS, MISSOURI, ASSIGNOR TO THE C. D. CHASE
SYRUP COMPANY, OF MISSOURI.

SHIPPING-CAN.

SPECIFICATION forming part of Letters Patent No. 437,094, dated September 23, 1890.

Application filed September 17, 1889. Serial No. 324,202. (No model.)

To all whom it may concern:

Be it known that I, CHARLES D. CHASE, of the city of St. Louis, in the State of Missouri, have invented a certain new and useful Improvement in Shipping-Cans, of which the following is a full, clear, and exact description, reference being had to the accompanying drawings, forming part of this specification.

My device consists of a sheet-metal can 10 closed in a cylindrical body of wood and having a removable cylindrical cap.

Figure I is a side elevation of the device. Fig. II shows a side elevation of the can proper with the case in axial section at II II, 15 Fig. I.

No novelty is claimed in the can 1, in the body 2 of the case, in the upper hoop 3, that extends above the top of the body, leaving an annular recess or channel at 4 to receive the 20 lower edge of the cap or top 5, in the cylindrical part 6 of the cap, or in the head 7. The head 7 and cylindrical part 6 are secured together by nails 8, which pass through the hoop 9.

25 10 are strips of tin or other material, whose upper ends are secured to the cap, while their lower ends are adapted to be secured to the body 2. The ends 11 of the strip are shown bent inward to engage beneath the edge of the hoop 3.

12 are nails or tacks by which the lower parts of the strips are fastened to the hoop.

I make the head with a recess 13 to receive the top of the can to brace the cap or top 5 30 against side jar or strain.

It will be seen that the top or cap will form a much-needed protection for the part of the can most liable to injury, and thus will in many cases prevent the breakage of the can, 40 with the resulting loss of contents, and injury to other articles over which the liquid might flow, or danger of fire resulting from the es-

cape of combustible liquid. Another great advantage is that the cans may be packed in bulk for shipment, the cans being placed one 45 upon another without any danger of injury, and thus the charge for transportation will be much reduced.

If preferred, the ends 11 of the strip may be respectively bent over the top 7 of the 50 cover and inserted beneath the edge of the hoop 3, as indicated in dotted lines in Fig. II, the upper ends being secured by tacks, as shown.

I claim as my invention—

1. A shipping-package having the following combination: a can 1, with cylindrical body and conical top, a case having a cylindrical body 2 fitting the body of the can, and a hoop 3, extending above the top of the body, forming an annular recess 4, a cap 5, with a recess 13, receiving the apex of the can, and a cylindrical part 6, whose lower edge fits within recess 4, and fastenings 10, adapted to secure the lid to the case, engaging at the lower end 65 the hoop 3 and fastened at the upper end to the cap, substantially as and for the purpose set forth.

2. In a shipping-package, the combination of the can 1, the case having a cylindrical body 2, with an annular recess 4, a cylindrical cap 5 6, the hoop 9 at the top of cap 5, the vertical fastening-strips 10, extending from the top of the cap 5 between the latter and the hoop 9 and alongside the side 6 of the cap 75 and secured to the top of the body 2, and nails or fastenings passing through the hoop and strips and into the head of the cap, substantially as shown and described.

CHARLES D. CHASE.
